BANNER MOUNTING CONSTRUCTION

Elliott J. Kies, Massillon, Ohio, assignor to The Massillon-Cleveland-Akron Sign Company, Massillon, Ohio, a corporation of Ohio

Filed May 2, 1961, Ser. No. 107,183

2 Claims. (Cl. 49—128)

This invention relates to banners or signs composed of fabric or other flexible sheetlike material and more particularly it pertains to means for mounting a flexible banner in a taut position to prevent its deterioration due to flapping or whipping caused by the wind which otherwise occurs where the banner is not mounted tautly in place.

Signs and banners of the flexible type which are composed of sheetlike fabric materials have been widely accepted as an advertising medium because of their low cost and upkeep. Such banners have a relatively short life compared to signs composed of other materials such as metal. Nevertheless, the life of fabric signs can be increased considerably by mounting the signs in such a manner that they will not sag or bulge or crease due to the normal action of wind.

It has been found that sheetlike banners composed of fabric materials can be used as signs for greatly extended periods of time where the banners are mounted tautly in such a manner that the entire banner, rather than any portion of it, moves with the wind. In that manner the action of the wind does not bend the surface of the sign and thereby cause the thread composing the fabric to bend back and forth and subsequently break and result in a tear in the material. Likewise, the fabric material of which the sign is composed is particularly receptive to paint and where the fabric is permitted to yield, the paint is gradually loosened and subsequently peels from the surface.

Accordingly, it is an object of this invention to provide a banner mounting construction which yields to various forces such as the wind without causing the usual sagging and whipping of the fabric material of which the banner is composed.

It is another object of this invention to provide a banner mounting construction which permits the banner to yield entirely to the action of wind or other objects without permitting any portion of the banner surface to bend, twist or sag and thereby result in ultimate local deterioration of the sign.

It is another object of this invention to provide a banner mounting construction which permits the entire sign to sway with movements of the wind or other objects by maintaining the banner in a rigid single plane.

These and other objects and advantages, apparent to those skilled in the art from the following description and claims, may be obtained, the stated results achieved, and the described difficulties overcome, by the apparatus, constructions, arrangements, combinations, subcombinations, elements, parts, and principles, which comprise the present invention, the nature of which is set forth in the foregoing general statements, a preferred embodiment of which—illustrative of the best mode in which applicant has contemplated applying the principles—is set forth in the following description and shown in the drawings, and

2

which is particularly and distinctly pointed out and set forth in the appended claims forming part hereof.

Generally, the banner mounting construction of the present invention may be described as comprising a sheetlike banner or sign composed of flexible fabric material, the banner being rectangular and having hem portions along opposite ends and edges, a rigid stiffening member disposed in each end hem portion, each stiffening member and corresponding banner hem portion having aligned apertures located on the longitudinal axis of the banner, banner mounting means including a bracket at each end of the banner, each bracket having a V-shaped configuration including a lower apex and upper end portions, each bracket being disposed along the surface of the banner and having its apex aligned with the apertures of the end hem portion and stiffening member, means extending through said apertures for securing the apex of said bracket to the banner, and the upper end portions of each bracket being pivotally attached to a bracket plate and each bracket plate being attached to the end surface of a horizontal member and spaced from each other by a distance substantially equal to the length of the banner.

In the drawings in which the preferred embodiment is shown by way of example:

FIGURE 1 is a perspective view of a flexible banner or sign mounted at its upper edge to the under surface of a portico or doorway of a service station;

FIG. 2 is a perspective view showing the manner in which the banner or sign yields to the movement of a high vehicle when necessary;

FIG. 3 is a fragmentary elevational view of one of the banners shown in FIG. 1;

FIG. 4 is an enlarged fragmentary rear elevational view, partly in section, showing the banner mounting construction;

FIG. 5 is a horizontal sectional view taken on the line 5—5 of FIG. 4;

FIG. 6 is a vertical sectional view taken on the line 6—6 of FIG. 4;

FIG. 7 is a perspective view showing one of the banner mounting brackets disposed in the horizontal storage position; and

FIG. 8 is an enlarged fragmentary sectional view showing the bracket in the storage position.

Similar numerals refer to similar parts throughout the drawings.

As shown in FIG. 1, a banner or sign is generally indicated at 1 and is attached to the under surface of a portico or canopy 2 which extends outwardly from a filling station 3. Likewise, a banner or sign 4 having a construction identical with that of the sign 1 is similarly mounted on the head 5 of a doorway 6. Each banner 1 and 4 is provided with banner mounting means including a V-shaped bracket 7 at each end of the banner.

The banners 1 and 4 are rectangular members for horizontal display which are adapted for temporary use in conspicuous locations where they cannot escape being noticed by potential customers.

Each banner 1 and 4 is a sheetlike member composed of a flexible material such as a fabric. The banner 1 includes an end hem portion 8, one of which is shown in FIG. 4, which is provided by folding over an end portion of the material and securing it to the back side of the

banner by stitching 9. A stiffening member 10 such as a wood slat is enclosed in each hem portion 8.

In addition, each banner 1 is provided with opposite edge hem portions 11 and 12 in which flexible stiffening members 13 such as rope are provided and secured in place by stitching 14. Moreover, an elongated envelope 15, which is composed of a fabric similar to that of the banner 1, is provided at spaced intervals along the banner 1, which envelope, as shown in FIG. 5, is composed of a folded over portion of material and stitched longitudinally at 16. In addition, a stretcher or stiffening member 17 is contained in each envelope which extends substantially between the upper and lower edge hem portions 11 and 12.

As shown in FIG. 4, the upper and lower ends of the envelope 15 are secured in place at 18 and 19 by the stitchings which form the upper and lower edge hem portions 11 and 12. As shown in FIG. 3, at least two envelopes 15 having stiffeners 17 mounted therein may be provided between opposite ends of the banner 1 in order to stretch the center portion and prevent the flat surface of the banner from becoming distorted due to the weather elements over a period of time.

As shown in FIG. 4, one of the pair of V-shaped brackets 7 is mounted on the back of the banner 1. The bracket includes a vertical portion 20 and an inclined portion 21 which form an apex 22 at their lower ends, which apex is aligned with apertures (not shown) extending through the fabric forming the hem 8 and an aperture in the wood slat 10. A nut and bolt assembly 23 extends through the apertures and the apex 22 and for convenience a washer 24 (FIG. 7) is secured, such as by welding, at the apex to hold the nut and bolt assembly 23 rigidly in place.

The upper ends of the vertical and inclined portions 20 and 21 are provided with outturned end portions 25 and 26, respectively. Each end portion 25 and 26 is pivotally mounted in a bearing 27, which in turn is seated in a pillow block 28. Each pillow block 28 is in turn secured by a rivet 29 to a mounting plate 30. Each plate 30 is attached to the under surface of a portico or the head 5 of a doorway by spaced toggle bolts 31, as shown in FIGS. 4 and 8. The spacing between the upper ends of the vertical and inclined portions 20 and 21 is preferably maintained by a spacer 32, the ends of which are secured to said portions by similar welds 33.

By such construction the banner mounting means or brackets 7 are held tightly in place at a spaced interval from each other, as shown in FIG. 3. The end surface portions of the banner 1 are held snugly against the vertical and inclined portions 20 and 21 which reinforce the banner and prevent it from twisting and turning in the wind. The inclined portions 21 hold the banner tautly in place between the brackets 7 by preventing the lower apices 22 from moving together slightly and thereby causing the banner to sag.

Accordingly, the spacing for the wood slats 10 at each end of the banner 1 is equal to the spacing between the apices 22 of the brackets 7. In that manner the banner 1 is free to swing back and forth on an axis extending through the aligned bearings 27 of the spaced brackets 7. In addition, as shown in FIG. 2, when a high vehicle passes under the banner 1, it is free to swing upwardly and out of the way without being damaged. The sign or banner 1 therefore does not interfere with the ordinary movement of traffic under the portico 2 or under the head 5 of the doorway 6.

Inasmuch as the signs 1 and 4 are composed of flexible fabric material, their useful life is relatively short compared to the banner mounting means such as the brackets 7, which are composed of elongated metallic rods. Accordingly, the banners 1 and 4 are preferably used intermittently such as during advertising campaigns of a specified nature, such as the introduction of a new product or service.

During the periods when the signs 1 and 4 are not in use the brackets 7 are stored in a horizontal position, as shown in FIGS. 7 and 8, by turning each bracket 7 upwardly from the vertical to the horizontal position and maintaining that position by turning a latch 34 into the position shown in FIG. 7. The latch 34 is a turn button pivotally mounted at 35 on the plate 30. By turning the latch 34 to the position shown in FIG. 7, it is disposed in the path of movement of the spacer 32 and thereby holds the bracket in the horizontal position.

The device of the present invention provides a banner mounting construction in which a flexible fabric banner may be used as a highly effective advertising medium for a specific advertising campaign. The device provides a relatively inexpensive cloth banner which is mounted and sustained in a single plane responsive to forces of the wind and other objects without detriment to the sign. By providing the spaced V-shaped brackets, the cloth banner may be rigidly mounted in place and sustained in a flat plane whereby it is free to sway with the wind as a rigid unit. In that manner the sign does not sag, wrinkle, crease, or bulge, which frequently results in repeated bending and subsequent breaking of the threads of the fabric of the sign.

The banner mounting construction of the present invention permits the fabric of the banner to stretch and dry tautly in the rain and sun. In the wind the entire unit is likewise preserved from flapping and subsequent fraying and tearing of the threads because the entire unit swings back and forth in the wind with no resulting damage whatsoever. The ropes in the edge margins prevent the banner from stretching unduly out of shape.

In the foregoing description certain terms have been used for brevity, clearness and understanding, but no unnecessary limitations have been implied therefrom as such words are used for descriptive purposes and are intended to be broadly construed.

Moreover, the embodiments of the improved construction illustrated and described herein are by way of example and the scope of the present invention is not limited to the exact construction shown.

Having now described the invention, construction, operation and use of a preferred embodiment thereof and the advantageous, new and useful results obtained thereby; the new and useful banner mounting construction and reasonable mechanical equivalents thereof obvious to those skilled in the art are set forth in the appended claims.

What is claimed is:

1. A banner mounting construction for fastening on a horizontal structure including an elongated banner composed of flexible sheetlike material and having vertical hem portions at opposite ends thereof, an elongated reinforcing member in and coextensive with each hem portion and having a flat surface, a pair of banner mounting brackets pivotally mounted at their upper ends on a horizontal structure and depending therefrom, the brackets being spaced from each other by a distance substantially equal to the length of the banner, each bracket being a V-shaped member having diverging leg portions providing an apex at the lower end thereof, the leg portion of one bracket nearer the other bracket being inclined upwardly, means detachably mounting each end portion of the banner on one corresponding bracket at its apex and holding the flat surface of the upper portion of the corresponding reinforcing member against one leg portion of the bracket to prevent rotation of said reinforcing member about the horizontal axis passing between the spaced apices of the brackets, the detachable mounting means also holding said flat portion against the other leg portion to prevent rotation of said reinforcing member about its longitudinal axis, whereby the flexible sheetlike banner is held tautly between the brackets in a wrinkle-free manner by the upwardly extending legs of each bracket and whereby the snug contact between the other

leg of each bracket and the upper end portion of the reinforcing member prevents rotation of the banner about its horizontal axis.

2. The banner mounting construction of claim 1 in which each V-shaped bracket has aperture means at its lower vertex, in which the detachable mounting means includes a nut and bolt assembly extending through the aperture means, in which the upper end portions of the legs of the V-brackets are turned outwardly for pivotal connection on a horizontal structure, and in which the

10 turned-out end portions of both brackets are disposed in a single axis of rotation.
